Primary Examiner — Mimosa De(74) *Attorney, Agent, or Firm* — Price Heneveld LLP(57) **CLAIM**

We claim the ornamental design for the chair, as shown and described.

DESCRIPTION

FIG. 1 is a perspective view of a chair embodying the present invention;

FIG. 2 is a front view of the chair;

FIG. 3 is a first side view of the chair;

FIG. 4 is a second side view of the chair;

FIG. 5 is a rear view of the chair;

FIG. 6 is a top view of the chair; and,

FIG. 7 is a bottom view of the chair.

The broken lines shown in the drawing are for illustrative purposes only and form no part of the claimed design.
